E. MoDONNELL.

COTTON PRESS.

No. 62,965.

PATENTED MAR. 19, 1867.

ONLY DRAWING ACCESSIBLE
TAKEN FROM PATENT OFFICE REPORT
1867 - VOL. III.

United States Patent Office.

EUGENE McDONNELL, OF BALTIMORE, MARYLAND.

Letters Patent No. 62,965, dated March 19, 1867.

IMPROVEMENT IN COTTON PRESS.

The Schedule referred to in these Letters Patent and making part of the same.

TO ALL WHOM IT MAY CONCERN:

Be it known that I, EUGENE McDONNELL, of Baltimore, in the county of Baltimore, and State of Maryland, have invented an improved Cotton Compresser; and I do hereby declare that the following is a full and exact description thereof, reference being had to the accompanying drawings, making part of this specification—

Figure 1 being a side elevation of the compressor.

Figure 2 a top view thereof.

Like letters designate corresponding parts in both of the figures.

The main object of my invention is to produce a cotton compressor which can be operated by horse power, and yet possess sufficient power for rapid compression. Another desideratum is to secure adequate strength of parts against the immense strain to which it is subjected with simple and economical means.

My compressor is an open one, so that the bale *x* can be had access to on all sides. The framework, which supports the other parts, consists simply of four posts, *A A A A*, framed into a suitable base, *B*. As this frame is not subjected to all the strain of the compression, it is not required to be so strong as otherwise it must be. The part which receives the whole force of the compression, and must resist the concentrated strain thereof, is a set of longitudinal iron beams, *C C C C*, placed horizontally at the upper part of the framework, to the posts *A A* of which they are secured by strong bolts, *m m*, passing through the posts and beams. These beams are not only of iron, but are massive, and placed vertically edgewise, substantially as represented. They become the fulcrum-blocks upon which the power levers *I I* are supported from above, and against which the bales are compressed upward from below, so that the powerful forces of these two actions are brought into direct antagonism to each other, and that through the mere compression of these beams, and therefore little liable to have a destructive action upon them. The bolts *m m*, which pass through and connect the posts *A A* and beams *C C*, also serve as pivots on which the toggle arms, *I I I I* of the power levers vibrate. There are arms, *L L*, both outside of the levers and between them, so as to multiply the strength and divide the strain as much as possible; and these likewise interweave with the beams *C C* for a like purpose. The toggle arms are pivoted to the power levers by bolts, *l l*, as represented. The power levers *I I*, on opposite sides of the press, are kept from separating, and at uniform distance apart, by connecting-bars, *K K*, and they are kept from approaching by guide standards, *D D*, which are braced apart by a cross-beam or beams, *d*. Friction-rollers, *i*, at the upper ends of the levers, relieve the friction of the contact with these guide standards. The power levers lift the follower *E* of the press directly, by means of very strong wrought-iron bands or rods, *M M*, which are attached at the upper ends to the levers by bolts, *k k*, or the equivalent thereof, and at their lower ends, to the follower, by extending down around the ends thereof, substantially as shown in fig. 1. The power of the horses is applied to the press by means of a capstan, *P*, or its equivalent, and a chain, *N*, which extends from the capstan first around pulleys, *p p*, attached to the frame of the press near the bottom, then around pulleys, *j j*, respectively at the ends of the levers *I I*, on opposite sides of the press, and is finally attached by its two ends to staples, *n n*, or their equivalent, on the frame of the press. The multiplication of power by these means is immense: first, the leverage of the capstan; then the doubling of the power by the pulleys *j j*; then the leverage of the levers *I I*, and finally, the toggle action of the toggle arms with the levers, the same rapidly increasing as the toggles approach a straight line, as required by the increasing resistance of the compressed bales. Thus a power sufficient to compress a bale of cotton to the desired extent is possible with a single horse, and the work is done very expeditiously. The press is adapted to different sizes of bales by adjusting the bed *G*. I accomplish the adjustment by the insertion of solid blocks or timbers, *H*, of different thickness, between the movable bed *G* and the fulcrum-beams *C C*. The bed *G* is moved up and down by means of cords or chains, *s s*, lifting at its four corners, then passing up over pulleys, *t t*, and finally winding around a windlass, *S*, which is turned by a cord, *T*, passing thence over a pulley, *v*, to a ratchet shaft and crank, *R*. The follower *E* is suitably strengthened by ribs, *c*, underneath.

What I claim as my invention, and desire to secure by Letters Patent, is—

A cotton-bale compressor provided with the following parts: Fulcrum-beams *C C*, power levers *I I*, toggle arms *L L*, lifting rods *M M*, rising follower *E*, adjustable upper bed *G*, and the whole driven by means of a

pulley chain, N, and capstan P, or its equivalent, to which the power of horses may be applied, all arranged and operating substantially as and for the purpose herein specified.

I also claim the combination of the fulcrum-beams C C, arranged between the follower E and power levers I I, through means of the toggle arms L L and lifting arms M M, substantially as herein set forth.

I also claim the adjustment of the bed G, by means of the blocks or timbers H, and the means described, or the equivalent thereof, for raising and lowering the bed, substantially as described.

I also claim the alternate arrangement or interweaving of the fulcrum-beams C C and toggle arms L L, as specified.

The above specification of my improved press for compressing cotton bales signed by me this day of December, 1866.

EUGENE McDONNELL.
